UNITED STATES PATENT OFFICE.

GERALD DEAKIN, OF ANTWERP, BELGIUM, ASSIGNOR TO WESTERN ELECTRIC COMPANY, INCORPORATED, OF NEW YORK, N. Y., A CORPORATION OF NEW YORK.

SELECTOR SWITCH.

Application filed September 13, 1924, Serial No. 737,476, and in Great Britain November 10, 1923.

This invention relates to automatic switches such as are used in automatic telephone exchange systems, and more particularly to switches of the group and final selector type in which the terminals of lines or trunks are arranged in fixed levels.

The primary object of this invention is to provide a switch in which a single set of brushes may be positioned for selecting a bank terminal in any level in a simple and economical manner.

In accordance with the chief feature of the invention the brush member is adapted to be moved to a predetermined position by a cam member which is selectively set to any desired position under the control of controlling impulses.

In the preferred form of carrying the invention into effect, a cam disc, carried by a flexible toothed disc which is rotated upon being brought into engagement with a continuously driven gear, is arranged so that impulses may be sent back, by means of an interrupter device operated as the cam disc rotates, to a registering mechanism under the control of which the switch operates. It will, however, be obvious that the invention is not limited to a switch of this type but may also be applied to a switch which is directly set by incoming impulses, in which case, the cam disc would be stepped around a sufficient distance to move the brush carriage one position for each impulse transmitted by the impulse transmitting device.

My invention will be better understood by reference to the accompanying drawings in which: Fig. 1 is a front elevation of the switch in accordance with the invention, portions of which are shown in section. Fig. 2 is a plan view showing in detail the form of the cam disc for moving the brush carriage, the flexible geared disc and the arrangement of the terminals. Fig. 3 is a view through line 3-3 in Fig. 1 and shows the means for connecting the brush assembly to the hollow shaft. Fig. 4 is a view through line 4-4 in Fig. 1 and shows the cam follower in detail.

Referring to the drawings, Fig. 1 shows a hollow tube 36 which is journaled in bearings 2 contained in switch frame 1 and is held in position by member 23 and nut 4 which secures a flexible toothed disc 30 of steel or other suitable material to the hollow tube 36. This gear 30 warps into engagement with the continuously driven gear 31 when

the clutch armature 32 of magnet 37 is operated. The lower end of hollow tube 36 contains a set screw 24 for adjusting the tension of the spiral spring 8. Tube 36 is slotted for a considerable portion as shown at 5. 60 A key 7 running diametrically across the interior of the tube 36 passes through slot 5 in order that it may slide up and down within the hollow tube but not rotate therein. Within the hollow tube 36 and between the key 7 and screw 24 is a spiral spring 8 which normally maintains the key 7 in its uppermost position as shown in Fig. 1 of the drawing.

Brushes 41, 42 and 43, which may be of any desired construction, are secured in an assembly of insulating material 6 between clamping plates 10 threaded on the ends of a sleeve 9 slidably mounted upon the hollow tube 36. The key 7 as shown more clearly 75 in Fig. 3, passes through the slot 5 from the interior of the hollow tube 36 around a portion of the periphery of the assembly 6 and is held in place by screws 40 so that the brush carriage may be moved up and down 80 the hollow shaft without rotating about it. This sliding movement is cared for by a mechanism to be hereinafter described.

A sleeve 11 which ends at 25 is placed over the upper end of hollow tube 36 and may be 85 rotated about the hollow tube and within the upper bearing 2. The sleeve is secured within the bearing by projection 50 and nut 14. To sleeve 11 are attached by means of nuts 12, 13 and 14 a flexible toothed disc 33 and a 90 cam disc 20. The whole may be rotated when the clutch armature 34 is attracted, permitting the flexible toothed disc 33 to warp into engagement with the continuously 95 rotating gear 35. Disc 33 is held in its normal position by armature 34 which is held in its normal position by spring 44.

Around the periphery of cam disc 20 are a series of notches 46. With the switch in its normal position roller 26 which is attached to spring 28 rests in the first notch. As the disc is rotated from one position to the next, springs 27 and 28 are opened and closed thereby transmitting impulses to the controlling mechanism of the register circuit.

On the cam disc 20 is mounted cam 19 having a continuous internal face which is perpendicular to the disc 20. This cam face is adapted to engage a roller 18, the purpose of 110

which is hereinafter described. With the switch in its normal position the face of the cam engaging roller 18 is at the maximum distance radially from the axis of the switch, 5 which is the center of the hollow tube 36. The cam face is so formed that as the disc is rotated from position to position roller 18 is forced radially toward the center, a distance equal to the desired displacement of 10 the brushes. In the usual switch of ten levels the cam face is so formed as to cause roller 18 to assume any one of ten positions, depending upon the number of steps to be selected.

15 Tube 36 terminates at 25. Extending from this point vertically and then horizontally is hollow tube 16 which is rigidly secured at its outer end to frame 1. Within tube 16 and extending down tube 36 and as 20 far as key 7, is a series of balls 15 movably mounted within tube 16. Slidably mounted within tube 16 through a slot therein is cam follower 17, one surface of which is engaged by the last ball. To cam follower 17 is attached the aforementioned roller 18 which engages the inner surface of cam 19. As 25 roller 18 is caused to move radially towards the center of the switch as previously described the series of balls are forced along 30 hollow tubes 16 and 36 forcing the key 7 and attached brush assembly down against the tension of spring 8. Gears 31 and 35 are fastened to shaft 49 which is driven continuously by a notch or other means.

35 The operation of the switch is as follows: When it is desired to lower brushes 41, 42 and 43 into a position opposite a particular arcuate level of contacts, clutch armature 34 is operated, thus permitting gear disc 33 40 to engage the driving gear 35 by means of which disc 20 and cam member 19 are rotated in the direction indicated by the arrow in Fig. 2. The engagement of cam 19 with the roller 18 causes cam follower 17 to 45 be forced along tube 16 towards the center of the disc, forcing steel balls 15 along hollow tubes 16 and 36 against the tension of spiral spring 8. During this movement the brushes are prevented from rotating by 50 means of the key 7 in slot 5 of tube 36 which is secured to gear 30 and held in its normal position by means of armature 32 and spring 47. As disc 20 rotates, contact is made between impulse springs 27 and 28 each time 55 roller 26 passes from one notch to the next thereby sending back impulses to the registering mechanism, (not shown), which operates in a well known manner. After the brushes have been lowered a sufficient number of steps, corresponding to the number of impulses sent back to the registering mechanism, the circuit of magnet 48 is opened thereby releasing armature 34 which in turn forces the flexible gear 33 out of engagement 60 with continuously rotating gear 35 thus stop-

ping the rotation of gear 33 and disc 20. The brushes are now rotated into contact with the desired terminals of the level chosen by means of magnet 37. When magnet 37 energizes, armature 32 is raised allowing the 70 flexible gear 30 to mesh with continuously revolving gear 31, thereby rotating hollow shaft 36 to which the brush assembly is attached. To stop the rotation of the switch, magnet 37 releases thereby forcing flexible 75 gear 30 out of mesh with the continuously revolving gear 31. The circuit arrangements for the control of the clutch magnets form no part of the present invention. Such circuits are well known to the art. 80

To restore the brush assembly to its normal position, cam disc 20 is again rotated in the same direction and brought to rest at a point 180° from the starting point. As the disc 20 rotates, the spring 8 forces the 85 key 7 and balls 15 upwardly moving the follower 17 to the end of tube 16. In this position it will be seen that roller 18 is again at the maximum distance from the axis of the switch and the pressure on the balls 15 90 in tube 16 is removed. The particular cam disc 19 which is shown in Fig. 2 is arranged for two complete selections per revolution. It will, however, be obvious that the cam face may be changed to increase or decrease 95 the number of complete or partial selections per revolution. It will be also understood that instead of driving the flexible gears 30 and 33 by means of continuously rotating members 31 and 35 respectively, the discs 100 could be rotated by means of a step-by-step mechanism under the control of impulses transmitted directly to the switch by any convenient means such as the well known calling device or dial. 105

What is claimed is:

1. In a selector switch, a rotatable shaft, a sleeve slidably and non-rotatably mounted on said shaft, a bank of contacts arranged in arcuate rows, a set of brushes carried by said sleeve for cooperation with said contacts, means for advancing said sleeve along said shaft to position said brushes opposite desired rows of said contacts, and means for rotating said shaft and sleeve to advance 110 said brushes along the selected rows of contacts.

2. In a selector switch, a rotatable shaft, a sleeve slidably and non-rotatably mounted on said shaft, a bank of contacts arranged in arcuate rows, a set of brushes carried by 115 said sleeve for cooperation with said contacts, a rotatable cam for advancing said sleeve along said shaft to position said brushes opposite desired rows of said contacts, and means for rotating said shaft and sleeve to advance 120 said brushes along the selected rows of contacts.

3. In a selector switch, a hollow rotatable shaft, a sleeve slidably and non-rotatably 125

5 mounted on said shaft, a bank of contacts arranged in arcuate rows, a set of brushes carried by said sleeve, a series of balls within said shaft, a rotatable cam, said balls being controlled by said rotatable cam for advancing said sleeve along said shaft to position said set of brushes opposite desired rows of said contacts and means for rotating said shaft and sleeve to advance said brushes 10 along the selected rows of contacts.

4. In a selector switch, a slotted rotatable shaft, a sleeve slidably mounted on said shaft, a pin carried by said sleeve engaging said slot in said shaft for transmitting the 15 rotational movement of said shaft to said sleeve, a bank of contacts arranged in arcuate rows, a set of brushes carried by said sleeve for cooperation with said contacts, means for advancing said sleeve along said 20 shaft to position said brushes opposite desired rows of said contacts, and means for rotating said shaft and sleeve to advance said brushes along the selected rows of contacts.

5. In a selector switch, a hollow rotatable shaft, a hollow angularly mounted extension for said shaft, a sleeve slidably and non-rotatably mounted on said shaft, a bank of contacts arranged in arcuate rows, a set of brushes carried by said sleeve for cooperation 25 30 with said contacts, a series of balls con-

tained in said shaft and extension and in engagement with said sleeve, a follower mounted within said extension for engagement with said balls, a rotatable cam co-operating with said follower for advancing 35 said balls along said extension and shaft, means for rotating said cam whereby said sleeve is advanced along said shaft to position said brushes opposite desired rows of 40 said contacts and means for rotating said shaft and sleeve to advance said brushes along the selected rows of contacts.

6. In a selector switch, a rotatable shaft, a sleeve slidably and non-rotatably mounted on said shaft, a bank of contacts arranged in arcuate rows, a set of brushes carried by said sleeve for cooperation with said contacts, means for advancing said sleeve along said shaft comprising a rotatable toothed disc having a cam thereon, an interrupter, 45 means cooperating with the teeth of said disc for operating said interrupter for controlling the advancement of said sleeve along said shaft to position said brushes opposite desired rows of said contacts, and means for 50 55 rotating said shaft and sleeve to advance said brushes along the selected rows of contacts.

In witness whereof, I hereunto subscribe my name this 21st day of August A. D., 1924.

GERALD DEAKIN.
